UNITED STATES PATENT OFFICE.

CHARLES C. RUSSELL, OF GREENFIELD, MASSACHUSETTS, ASSIGNOR TO RUSSELL MANUFACTURING COMPANY, OF GREENFIELD, MASSACHUSETTS, A CORPORATION OF MASSACHUSETTS.

SCREW-PLATE.

1,083,340.

Specification of Letters Patent.

Patented Jan. 6, 1914.

Application filed September 25, 1912, Serial No. 722,305. Renewed June 4, 1913. Serial No. 771,732.

To all whom it may concern:

Be it known that I, CHARLES C. RUSSELL, a citizen of the United States, residing at Greenfield, in the county of Franklin and 5 State of Massachusetts, have invented certain new and useful Improvements in Screw-Plates; and I do hereby declare the following to be a full, clear, and exact description of the invention, such as will enable others 10 skilled in the art to which it appertains to make and use the same.

My invention relates to improvements in screw plates, and it consists in the constructions, combinations and arrangements here- 15 in described and claimed.

An object of my invention is to provide an improved screw plate having means for automatically unlocking the die-members and quickly shifting the latter to open position 20 upon the completion of a thread.

A further object of my invention is to provide an improved screw plate, in which the die members will be automatically closed to an accurately adjusted size and locked 25 firmly in position by a single movement of the collet.

In the accompanying drawings forming a part of this application, and in which similar reference symbols indicate corresponding parts in the several views:—Figure 1 is a rear face view, partly broken away, illustrating one embodiment of my invention with the die-members adjusted in operative position; Fig. 2 is a similar view showing 35 the die-members shifted into their open, or inoperative, position; Fig. 3 is a front face view of the construction shown in Figs. 1 and 2; and Fig. 4 is a section on the line 4—4 of Fig. 1.

Referring to the drawings, 1 indicates a stock, or other frame, provided with cam faces 2 adapted to engage projections 3 on die members 4, slidably mounted in a collet 5 rotatably mounted in said stock. Any 45 suitable means may be employed for securing a delicate adjustment of the die-members, such as screwing the threaded pins 3 in or out of the die members. A pin 6 is shown threaded in the collet 5 and extending 50 through a slot 7 in the stock for limiting the rotation of said collet; the slot 7 being so proportioned that when the pin 6 is in engagement with one end thereof, the projections 3 will be in engagement with the 55 inner periphery of the stock at 8 for adjust-

ing the die-members to their operative position, and when said pin 6 is in engagement with the other end of the slot 7, the projections 3 will be in position for engaging the deepest portions 9 of the cam faces 2 for permitting shifting of the die-members 4 to their open position. 60

The pins 6 are shown provided with flattened sides for fitting the slot 7, and adapted to be turned through 180° in enlargements 7× 65 at the respective ends of said slot for locking the collet firmly in position.

Any suitable means may be employed for maintaining the projections 3 in engagement with the cam faces 2, such as springs 10 confined between the opposite die-members 4; if desired, the springs could be omitted by providing the projections 8 with offsets fitting within cam grooves in the stock 1. 70

A guide 11 is threaded into the collet 5 75 for clampingly engaging the die members 4 to firmly lock the latter in their adjusted position. I have shown the guide provided with a projection, or tooth, 12 adapted to engage within a series of recesses 13 formed in a ring 14, which latter is adjustably locked to the stock 1 by a tapered pointed screw 15 engaging a V-shaped slot 16 in said ring. This permits the necessary slight adjustment of said ring 14 to insure the engagement of the guide tooth 12 within a recess thereof. If desired, any suitable means could be formed integral with the stock for locking the guide for preventing 80 rotation of the latter. 85 90

From the above description, it will be clear that upon rotation of the collet from the position shown in Fig. 1, said collet will be screwed upwardly on the guide 11 to release the die-members 4 from the clamping 95 action of said guide, and the projections 3 will then engage the cam faces 2 to permit shifting of said die-members to their open inoperative position. The reverse of this operation takes place when the collet is shifted in the opposite direction. 100

I have illustrated and described preferred and satisfactory constructions, but changes could be made within the spirit and scope of my invention. 105

I claim:—

1. In a screw-cutting device, a stock, a collet rotatably mounted in said stock, die-members adjustably mounted in said collet, means for rotating said collet, and independ- 110

ent means for automatically opening and closing said die members and locking the latter in their closed position upon rotation of said collet.

5 2. In a screw-cutting device, a stock provided with cam faces, a collet rotatably mounted in said stock, means for rotating said collet, die members slidably mounted in said collet and provided with projections 10 engaging said cam faces, a guide on said collet, and means for automatically shifting said guide into clamping engagement with said die members upon rotation of said collet.

3. In a screw-cutting device, a stock provided with cam faces, a collet rotatably mounted in said stock, means for rotating said collet, die members slidably mounted in said collet and provided with projections 15 engaging said cam faces, a guide threaded 20 in said collet for clamping engaging said

die-members, and means for locking said guide against rotation on said stock.

4. In a screw-cutting device, a stock provided with cam faces, a collet rotatably mounted in said stock, means for rotating 25 said collet, die members slidably mounted in said collet and provided with projections, means for maintaining said projections in engagement with said cam faces, a guide on said collet, and means for automatically 30 shifting said guide into clamping engagement with said die members upon rotation of said collet.

In testimony whereof, I affix my signature, in presence of two witnesses.

CHARLES C. RUSSELL.
